[57] CLAIM

The ornamental design for a bicycle carrier, as shown and described.

DESCRIPTION

FIG. 1 is a front elevational view of a bicycle carrier showing my new design;

FIG. 2 is a left side elevational view thereof, the right side elevational view being a mirror image thereof;

FIG. 3 is a top plan view thereof;

FIG. 4 is a bottom plan view thereof; and,

FIG. 5 is a rear elevational view thereof.

The bar shown in FIGS. 1, 2 and 5 is shown broken away to indicate indeterminate length.
